UNITED STATES PATENT OFFICE.

GEORGE SIMON AND FRITZ BALZER, OF CHICAGO, ILLINOIS, ASSIGNORS TO TROY LAUNDRY MACHINERY COMPANY, A CORPORATION OF NEW YORK.

REVERSING MECHANISM FOR WASHING-MACHINES.

1,264,340.

Specification of Letters Patent.

Patented Apr. 30, 1918.

Application filed February 8, 1915. Serial No. 6,940.

To all whom it may concern:

Be it known that we, GEORGE SIMON, a citizen of the United States, residing at Chicago, in the county of Cook and State of Illinois, and FRITZ BALZER, a subject of the Emperor of Germany, residing at Chicago, in the county of Cook and State of Illinois, have invented certain new and useful Improvements in Reversing Mechanism for 10 Washing-Machines, of which the following is a specification.

Our invention relates in general to mechanism for reversing moving parts of machines, and more particularly to mechanism 15 for automatically reversing the direction of rotation of the cylinders of washing machines.

In the operation of various machines it is desirable to periodically reverse the direction 20 of movement of certain parts, such for instance as the cylinders of washing machines, the direction of rotation of which is periodically reversed in order that the articles may be agitated and directly subjected 25 to the action of the suds.

The primary object of our invention is to provide mechanism for reversing the moving parts of a machine which will be actuated by the movement of the reversible parts 30 to so change the application of power to the machine as to effect the reversing of the machine.

A further object of our invention is to provide an electrically driven cylinder 35 washing machine with reversing mechanism controlled by the rotation of the cylinder to effect the periodical reversal of the direction of rotation of the cylinder.

A still further object of our invention is 40 to provide mechanism for reversing a moving part of a machine which will be efficient in operation, durable in use, and comparatively simple in construction.

Our invention will be more fully disclosed 45 hereinafter with reference to the accompanying drawings, in which the same is illustrated as embodied in two convenient and practical forms, and in which,—

Figure 1 is an end elevational view of a 50 cylinder washing machine equipped with our invention;

Fig. 2 is an enlarged elevational view of the mechanism actuated by the rotation of the cylinder;

Fig. 3 is a side elevational view looking 55 from the right in Fig. 2;

Fig. 4 is an end elevational view of a cylinder washing machine equipped with a modified form of our invention; and,

Fig. 5 is an enlarged elevational view of 60 the reversing mechanism detached from the machine shown in Fig. 4.

Similar reference characters are used to designate similar parts in the several figures of the drawings. Reference character A 65 designates one end wall of the tank of a cylinder washing machine of well-known construction. B designates one of the end trunnions of the usual cylinder b, inclosed by the tank A and adapted to contain the 70 articles to be washed. The structural details of the washing machine are not illustrated or disclosed, inasmuch as they do not in themselves form parts of our invention, and a specific description of them is unnecessary to a complete understanding of our invention.

C designates an electric motor mounted upon any suitable support D. The motor is connected through a suitable train of gearing, such as a pinion c, a gear wheel d, and gear wheel e, with a gear wheel (not shown) fixed to the trunnion of the cylinder which projects from the opposite side of the machine to that shown in Fig. 1. 85

The trunnion B has fixed thereto a ring F, on the periphery of which is carried a plurality of equidistant radial projections f. A lever G is pivotally supported at its upper end upon a post G¹ projecting outwardly 90 from a plate H, secured to the end wall A of the tank of the machine by any suitable means, such for instance as a plurality of brackets H¹—H² and H³. The lower end of the lever G carries an antifriction roller g, 95 which normally lies in the path of rotation of the projections f.

Loosely mounted upon the portion of the post G¹, adjacent the upper end of the lever G, is a ratchet wheel J, the teeth of which are engaged by a spring-actuated pawl j carried by the lever G. The pawl is retained in contact with the periphery of the ratchet wheel by any suitable means, such for instance as a coiled spring j¹ connecting the tail of the pawl with the adjacent portion of the oscillatory lever G. A gravity pawl I is mounted upon the supporting plate H in 100 105

position to engage the teeth of the ratchet wheel J and retain the ratchet wheel against reverse movement. i designates the weight of the pawl I for retaining the same normally in contact with the periphery of the ratchet wheel J.

Mounted upon the post G¹, adjacent the inner surface of the ratchet wheel J, is a cam K which is non-rotatably connected 10 with the ratchet wheel by means of a pin k . The cam K is provided with two substantially semicircular surfaces K¹ and K², the former having a greater radius than the latter. A shoulder k^1 is formed on the cam 15 K intermediate two adjacent ends of the cam surfaces K¹ and K², while an inclined surface k^2 connects the opposite adjacent ends of the cam surfaces K¹ and K².

Fulcrumed upon the plate H, adjacent the 20 top thereof, is a bell crank lever L, carrying an antifriction roller l on the short-arm thereof, which rests upon the periphery of the cam K. The upwardly projecting arm of the bell crank lever L is connected by a 25 link L' with an electric switch M, comprising a bell crank lever m, which carries two oppositely projecting contact blades M¹ and M², adapted to alternately engage stationary contacts m¹ and m², respectively, when the 30 bell crank lever m is oscillated. A spring m³ is connected to the opposite arm of the bell crank lever m from that to which the link L is connected, said spring serving to oscillate the bell crank lever m to close the circuit 35 through movable contact M¹ and fixed contact m¹ when the cam surface K² passes beneath the antifriction roller l on the bell crank lever L. The switch M controls a circuit for effecting the reversal of direction of rotation of the electric motor C.

Inasmuch as our present invention is not concerned with any particular arrangement of motor circuit, we have not deemed it necessary to illustrate and disclose electrical 45 connections through the medium of which the switch M reverses the direction of rotation of the motor. The switch M, which comprises the bell crank lever m, the blades M¹ and M², and the fixed contacts m¹ and 50 m², may be supported in any suitable manner, as by means of a bracket M³ fixed to the tank of the machine.

In order to automatically return the oscillatory lever G to a position in the path of the projections f, after it has been oscillated by said projections, we provide a gravity member comprising a plate N supported adjacent its top by means of posts O¹ and O², supported upon the plate H. The said posts 55 extend through slots n¹ and n², respectively, in the plate N. The lower edge of the plate is provided with an angular notch n which surrounds a stud g¹ on the lever G. The plate N is provided with a weight P at the 60 portion thereof adjacent the slot n¹. If de-

sired, the plate N may have the requisite weight given to it for performing the necessary functions in any other suitable manner.

The operation of our improved reversing mechanism is as follows: The rotation of the 70 cylinder causes the radial projections f to successively engage the lower end of the lever G and to oscillate the same in a direction corresponding to the direction of rotation of the trunnion B of the cylinder. 75 When the trunnion B rotates in the direction of the arrow in Fig. 1, the lever G is successively oscillated toward the right, thereby rotating the ratchet wheel J step by step through the engagement therewith 80 of the pawl j on the lever G. Each oscillation of the lever G toward the right oscillates the plate N about the post O¹ as a fulcrum, such oscillation being permitted by the upward movement of the slot n² around 85 the post O². Such oscillation is imparted to the plate N through the engagement of the stud g¹ on the lever G, with the inclined edge at the right of the recesses n in said plate. When each projection f has oscillated the lever G to the right sufficiently to pass beneath the lower end of said lever, the weight of the plate N, acting through its engagement with the stud g¹, returns the lever G to its normal central position in the 90 path of the projections f, so that it will be engaged by the succeeding projection and again oscillated toward the right. Each oscillation of the lever G toward the left causes the pawl j to engage a succeeding 95 tooth of the ratchet wheel J, so that each oscillation of the lever G toward the right rotates the ratchet wheel a step corresponding to the angular oscillation of the lever G. When the ratchet wheel J has been moved 100 105 step by step a sufficient distance for the antifriction roller l on the lower end of the bell crank lever L to engage the inclined cam surface k, the bell crank lever L is oscillated by reason of the antifriction roller l 110 moving outwardly by reason of the passing beneath it of the cam surfaces K¹ of greater radius than the cam surfaces K². This oscillation of the bell crank lever L oscillates the switch M, through the medium of the link 115 L', from the position shown in Fig. 1 into a position in which the blades M² will engage the fixed contacts m², such oscillation of the switch instantly disengaging the blade M¹ from the fixed contact m¹. This movement 120 of the switch M changes the circuit conditions so as to reverse the motor and to thereby reverse the direction of rotation of the cylinder of the machine.

The reversal in the direction of rotation 125 of the cylinder, of course, reverses the direction of rotation of the trunnion B, so that the projections f carried thereby move in a path opposite to that indicated by the arrow in Fig. 1. As each projection f engages 130

the oscillating lever G, it is moved toward the left, and the pawl *j* thereon is engaged with another tooth on the ratchet wheel J. The rotation of the lever G toward the left 5 swings the plate N upwardly about the post O² as a fulcrum, such movement being permitted, by the slot *n*¹ moving relatively to the post O¹ extending therethrough. This oscillation of the plate N is effected through 10 the engagement of the stud *g*¹ on the lever G with the inclined edge at the left of the notch *n* in the plate. Immediately upon each projection *f* passing beneath the antifriction roller on the lower end of the lever G, the 15 latter is oscillated toward the right by reason of the weight of the plate N applied to the lever through the engagement of the edge of the notch *n* with the stud *g*¹. The lever G is therefore returned to its central position 20 in the path of the next projection *f*, while at the same time the ratchet wheel J, and with it the cam K, have been stepped toward the right.

When the cam has been moved relatively 25 to the lower end of the bell crank lever L a distance corresponding to the surface of the cam K¹, the roller *l* moves inwardly on to the shoulder *k*¹, permitting the oscillation of the bell crank lever L by the tension of 30 the spring *m*³ exerted through the ball crank lever *m* of the switch and the connecting link L. During the instant that the roller *l* rests upon the shoulder *k*¹, the switch M is in a neutral position, such neutral position being 35 accomplished only momentarily, as the momentum of the cylinder causes the same to continue its rotation and thereby rotate the cam K the distance of one tooth of the ratchet wheel J, so that the cam surfaces K² 40 pass under the roller *l*. This movement of the bell crank lever L permits the spring *m*³ to oscillate the switch M to the position shown in Fig. 1, in which the circuit through the blade M² and fixed contact *m*² has been 45 broken and a circuit established through the blade M¹ and fixed contact *m*¹ to reverse the direction of the motor, and consequently the direction of rotation of the cylinder. 50 The cylinder continues to rotate in its reversed direction until the cam surface K² has passed the antifriction roller *l* on the inner end of the bell crank lever L, and the inclined surface *k*², which connects the cam surface K² with the cam surface K¹, oscillates the bell crank lever L and again reverses the motor through the oscillation of 55 the switch M. The inclined surfaces *k*² and the shoulder *k*¹, which connect the adjacent ends of the cam surfaces K¹ and K², are 60 important in that the antifriction roller *l* rests upon the inclined surface *k*² during the oscillation of the ratchet wheel J a distance of one tooth, and during that interval retains the switch M in a neutral position, 65 while the shoulder *k*¹ accomplishes a similar

object when the roller *l* passes from the cam surface K¹ to the cam surface K², namely, it supports the roller *l* during the interval of the movement of the ratchet wheel a distance of one tooth, and hence retains the switch M 70 in a neutral position during such interval. The cam surfaces, together with the inclined contacting surfaces *k*², and the shoulder *k*¹, serve to so actuate the switch M that the motor is driven in one direction, is then disconnected from the current, is then driven in 75 a reversed direction, and then is again disconnected from the current.

Should the operation of the machine be discontinued at a time when the switch M is 80 in a neutral position, it may be moved so as to engage the blade M¹ with the fixed contact *m*¹, or to engage the blade M² with the fixed contact *m*², by moving the rod R, mounted upon the end frame A of the machine, such rod being provided with pins *r*¹ and *r*², either of which may engage the lever G and oscillate the same a distance of one tooth of the ratchet wheel J, to move 85 the cam the slight distance necessary to permit the oscillation of the bell crank lever L to a position in which the switch M will be moved into one of its circuit-closing positions.

In the modified form of our invention 90 shown in Figs. 4 and 5, the switch for reversing the current to the motor is mounted on one end of the tank adjacent the mechanism for oscillating the same. In this form of our invention a sprocket wheel S is fixed 100 upon the trunnion B at one end of the cylinder of the washing machine, and is connected by a sprocket chain *s* with a sprocket wheel S¹ at the end of a stub shaft *s*¹ located at one side of the trunnion B. The stub shaft is mounted in the lower end of a casing S², having a base plate *s*² fixed to the adjacent end wall of the tank of the washing machine. A ring F¹, having equidistant radial projections *f*¹, similar to the ring F having projections *f* on the form of our invention shown in Figs. 1, 2 and 3, is fixed upon the stub shaft *s*¹ and located within the bottom of the casing S². The projections *f*¹ successively engage and oscillate the lever G, which, through the mechanism shown in Figs. 1, 2 and 3, effect the oscillation of the bell crank lever L for actuating the switch. Inasmuch as the mechanism actuated by the projections *f*¹ 110 for oscillating the bell crank lever L, in the form of our invention shown in Figs. 4 and 5, is the same in construction and operation as the correspondingly designated mechanism of the form of our invention 115 shown in Figs. 1, 2 and 3, detailed description thereof need not be repeated. The bell crank lever L is connected by a link T with a crank arm *t*, fixed to a rock shaft T¹, journaled upon the bearings *t*¹, suitably sup- 120 125 130

ported upon a base T^2 , fixed to the back plate s^2 of the casing S^2 . Oppositely projecting contact blades U^1 and U^2 are fixed to the rock shaft T' , and are adapted to 5 alternately engage stationary contacts u^1 and u^2 mounted upon the base T^2 . A spring V is connected at one end to the base plate s^2 , and at its other end to a crank arm v fixed to the rock shaft T , the tension of the 10 spring serving to oscillate the rock shaft so as to move the contact blade U^2 into engagement with the fixed contact u^2 , and to simultaneously disengage the contact blade U^1 from the fixed contact u^1 , such action of the 15 spring only occurring when the cam surface K^2 of the cam K passes beneath the roller l on the short-arm of the bell crank lever L . Fixed to the end of the rock shaft T' , which projects through the casing S , 20 is a lever W for manually oscillating the rock shaft T' to engage the contact blade U^1 with the fixed contact u^1 , should the switch blades have been left in a neutral position when the machine was previously 25 stopped.

The operation of the form of our invention shown in Figs. 4 and 5 is substantially the same as the operation of the form of our invention shown in Figs. 1, 2 and 3. The 30 rotation of the cylinder serves to periodically reverse the current to the motor C^1 , and thereby reverse the direction of rotation of the cylinder. The motor C^1 is operatively connected to rotate the cylinder through 35 any suitable train of gears, such for instance as gear c^1 fixed to the motor shaft, which meshes with a larger gear d^1 , which in turn meshes with a gear wheel e^1 , in mesh with a large gear wheel b^1 , fixed to the 40 trunnion of the cylinder on the opposite side of the machine from that shown in Fig. 4.

From the foregoing it will be observed 45 that we have invented an improved mechanism for reversing the direction of movement of a machine, which although illustrated and described in connection with an electrically-driven cylinder washing machine, is applicable to other machines, 50 whether driven by an electric motor or other power connection.

While we have illustrated and described in more or less detail a specific embodiment 55 of our invention herein disclosed, yet we wish it understood that we do not desire to be limited thereto, as we contemplate changes in form, the proportion of parts, and the substitution of equivalents as circumstances may require or as may be deemed 60 expedient.

We claim:—

1. A machine comprising a movable member, means for driving said member, a movable projection actuated by the movement 65 of said member, an oscillatory lever extend-

ing into the path of said projection and oscillated thereby, a pawl on said lever, a ratchet wheel rotated by the successive engagements therewith of said pawl, a weight lifted by each oscillation of said lever by 70 said projection, said weight serving to return said lever into the path of said projection and to thereby impart movement to said ratchet wheel, and means actuated by said ratchet wheel to periodically reverse 75 the direction of movement of said driving means.

2. A machine comprising a rotary member, driving means for said member, a movable projection actuated by the rotation of 80 said member, an oscillatory lever extending into the path of said projection and oscillated thereby, a pawl on said lever, a ratchet wheel rotated by the successive engagements therewith of said pawl, a weight lifted by each oscillation of said lever by 85 said projection, said weight serving to return said lever into the path of said projection and to thereby impart movement to said ratchet wheel, a cam movable with 90 said ratchet wheel, and mechanism operated by said cam to periodically reverse the direction of movement of said driving means.

3. A machine comprising a rotary member, an electric motor for rotating said member, a movable projection actuated by the rotation of said member, an oscillatory lever extending into the path of said projection and oscillated thereby, a pawl on 95 said lever, a ratchet wheel rotated by the successive engagements therewith of said pawl, a weight lifted by each oscillation of said lever by 100 said projection, said weight serving to return said lever into the path of said projection and to thereby impart movement to 105 said ratchet wheel, a cam movable with said ratchet wheel, a switch for effecting the reversal of current through said motor, and operative connections between said cam and switch for oscillating 110 the latter to periodically reverse the current through said motor.

4. A machine comprising a movable member, driving means for moving said member, a movable projection actuated by the movement of 115 said member, a reciprocating element extending into the path of said projection and moved thereby in one direction to a position out of the path thereof, a gravity member 120 engaging said reciprocating element to return the same into the path of said projection after each movement thereof by said projection, and mechanism actuated by the reciprocation of said element to periodically 125 reverse the direction of movement of said driving means.

5. A machine comprising a rotary member, driving means for said member, a movable projection actuated by the rotation of 130 said member, an oscillatory lever extending

into the path of said projection and oscillated thereby to a position out of the path thereof, a gravity member engaging said lever to return the same into the path of 5 said projection after each oscillation thereof by the engagement therewith of said projection, and mechanism actuated by the oscillation of said lever to periodically reverse the direction of rotation of said driving 10 means.

6. A machine comprising a rotary member, an electric motor for rotating said member, a projection rotated by said member, an oscillatory lever extending into the path of 15 said projection and oscillated thereby, a gravity member engaging said lever to normally maintain the same in the path of said projection and to return said lever to said normal position after each oscillation there- 20 of by said projection, and mechanism actuated by the oscillation of said lever to periodically reverse the current through said motor.

7. A machine comprising a movable mem- 25 ber, means for driving said member, a series of spaced projections rotated by said member, a reciprocating element extending into the path of said projections and successively moved by them, a gravity member engaging 30 said element to return the same into the path of said projections after each movement thereof by them, and mechanism actuated by the reciprocations of said element to periodically reverse the direction of movement 35 of said driving means.

8. A machine comprising a rotary member, driving means for rotating said member, a series of spaced projections rotated by said member, a lever extending into the 40 path of said projections and successively os- cillated by them, a gravity member engag- ing said lever to return the same into the path of said projections after each oscillation thereof, and mechanism actuated by 45 the oscillation of said lever to periodically reverse the direction of said driving means.

9. A machine comprising a rotary mem- 50 ber, an electric motor for rotating said mem- ber, a series of spaced projections rotated by said member, a lever extending into the

path of said projections and successively oscillated by them, a gravity member en- gaging said lever to return the same into the path of said projection after each oscil- lation thereof, and mechanism actuated by 55 the oscillation of said lever to periodically reverse the current through said motor.

10. A machine comprising a movable mem- ber, driving means for said member, a series of projections rotated by said member, an 60 element extending into the path of said pro- jections and successively moved by them, gravity means engaging said element to re- turn the same into the path of said projec- tions after each successive movement thereof 65 by said projections, a pawl on said element, a ratchet wheel rotated by the successive en- gagements therewith of said pawl, a cam 70 movable with said ratchet wheel and having two curved surfaces of different radius con- nected by an intermediate surface, a lever 75 engaging said cam and oscillated thereby, and mechanism operated by said lever to effect the periodical reversal of the direction of movement of said driving means.

11. A machine comprising a rotary mem- ber, driving means for rotating said mem- ber, a series of projections rotated by said member, a lever extending into the path of said projections and oscillated through en- gagement therewith, a gravity member en- gaging said lever to return the same into the path of said projections after the suc- cessive oscillations thereof by said projec- tions, a pawl on said lever, a ratchet wheel 80 85 rotated by the successive engagements there- with of said pawl, a cam movable with said ratchet wheel, a lever engaging said cam and oscillated thereby, and means operated by the oscillation of said latter lever to effect 90 the periodical reversal of the direction of rotation of said driving means.

In testimony whereof, we have subscribed our names:
